(57) **CLAIM**

The ornamental design for a vehicle lift platform hand switch, as shown and described.

DESCRIPTION

FIG. 1 is a front perspective view of a vehicle lift platform hand switch that shows our new, original and ornamental design.

FIG. 2 is a left side view of the vehicle lift platform hand switch of FIG. 1.

FIG. 3 is a right side view of the vehicle lift platform hand switch of FIG. 1.

FIG. 4 is a front view of the vehicle lift platform hand switch of FIG. 1.

FIG. 5 is a rear view of the vehicle lift platform hand switch of FIG. 1.

FIG. 6 is a top view of the vehicle lift platform hand switch of FIG. 1; and,

FIG. 7 is a bottom view of the vehicle lift platform hand switch of FIG. 1.

The broken lines in the drawings depict portions of the vehicle lift platform hand switch that form no part of the claimed design.
